UNITED STATES PATENT OFFICE.

HERMAN P. RANDALL, OF PASADENA, CALIFORNIA, ASSIGNOR TO KEMP MANUFACTURING CO., OF LOS ANGELES, CALIFORNIA, A CORPORATION OF CALIFORNIA.

DRAWER-STOP.

1,227,001.

Specification of Letters Patent.

Patented May 22, 1917.

Application filed February 8, 1916. Serial No. 77,004.

To all whom it may concern:

Be it known that I, HERMAN P. RANDALL, a citizen of the United States, residing at Pasadena, in the county of Los Angeles and State of California, have invented a new and useful Drawer-Stop, of which the following is a specification.

My invention relates to the art of building and furniture construction, and the principal object of the invention is to provide a stop which may be incorporated in drawer structure as used in such construction.

In the drawing, which is for illustrative purposes only:

Figure 1 is a perspective view of my invention.

Fig. 2 is a view of this invention in place in a drawer structure, the structure being shown in section to better illustrate the invention.

Fig. 3 is a section through the drawer structure on a plane represented by the line x^3-x^3 of Fig. 2.

The stop which I use in my invention consists of a single piece of metal 11, bent in the form shown in Fig. 1 to form side prongs 12, a side guide portion 13, a bottom guide portion 14, a stop arch 15 and a bottom lug 16, the bottom lug 16 having a screw opening 17 formed therein.

The stops are installed at both sides of the drawer and near the front thereof. The method of installation is shown in Fig. 2, in which 21 is a side structure, and 22 is a bottom structure, in which a drawer 23 slides, the drawer consisting of sides 24, a bottom 25, and a front 26. In the ordinary types of construction the front 26 is secured at either side to the sides 24, and the bottom 25 is mortised into the sides 24 and the front 26 at approximately one-half inch above the bottom of the sides and front.

My invention is located as shown in Figs. 2 and 3. The prongs 12 are driven into the side 21, and the lug 16 is fastened in place by a screw 31 which is placed in the opening 17. The portions 13 and 14 are concaved as shown in Fig. 1, the side guide portion 13 bearing against the side of the drawer 24, and providing a smooth surface on which it may slide, the weight of the drawer being taken on the portion 14, it being, of course, understood that there is one of the stops 11 at each side of the drawer. The arch stop

portion 15 of each of the stops 11 projects up inside the drawer to a point close to the bottom 25 thereof, the members 11 being so located that the front 26 of the drawer strikes against the arch stop 15 when the drawer is pushed back into place, thereby effectually preventing over-travel and accurately alining the front of the drawer 26 to the furniture, or building construction in which the drawer is installed.

I claim as my invention:

1. A drawer stop for use in a drawer structure to guide and stop a drawer, comprising two strips of metal secured in said drawer structure, one at each side thereof, said strips each comprising a stop portion extending upwardly inside the drawer below the bottom of said drawer in such a position as to be struck by the front of the drawer with the drawer in the closed position, a side portion formed on said strip in such a position as to guide the side of said drawer, and a bottom guide portion formed on said strip in such a position as to provide a support and a guide for the bottom of the side of said drawer, said metal members being so located that the front of the drawer is stopped in proper alinement with the drawer structure when in said closed position.

2. A drawer stop for use in a drawer structure to guide and stop a drawer, comprising two strips of metal secured in said drawer structure, one at each side thereof, said strips each comprising a stop portion extending upwardly inside the drawer below the bottom of said drawer in such a position as to be struck by the front of the drawer with the drawer in the closed position, a convex side portion formed on said strip in such a position as to guide the side of said drawer, and a convex bottom guide portion formed on said strip in such a position as to provide a support and a guide for the bottom of the side of said drawer, said metal members being so located that the front of the drawer is stopped in proper alinement with the drawer structure when in said closed position.

3. A drawer stop for use in a drawer structure to guide and stop a drawer, comprising two strips of metal secured in said drawer structure, one at each side thereof, said strips each comprising a stop portion extending upwardly inside the drawer be-

low the bottom of said drawer in such a position as to be struck by the front of the drawer with the drawer in the closed position, a convex side portion formed on said strip in such a position as to guide the side of said drawer, side prongs formed on said side portion in such a location that they can be driven into the side of said drawer structure, and a convex bottom guide portion formed on said strip in such a position as

to provide a support and a guide for the bottom of the side of said drawer, said metal members being so located that the front of the drawer is stopped in proper alignment with the drawer structure when in said closed position.

In testimony whereof, I have hereunto set my hand at Los Angeles, California, this 2nd day of February, 1916.

HERMAN P. RANDALL.
